MISSILE AUTOPILOT

Donald E. Cole, West Covina, Calif., assignor to General Dynamics Corporation, San Diego, Calif., a corporation of Delaware

Filed July 6, 1961, Ser. No. 122,171
10 Claims. (Cl. 244—3.16)

This invention relates to guided missiles, and more particularly, to a proportional control automatic pilot suitable for controlling the flight path of a rolling type of guided missile.

A rolling type of guided missile wherein the present invention may be employed rotates continually in flight about its longitudinal axis. A pair of laterally opposed, fixed incidence lift producing aerodynamic surfaces, which may be readily and rapidly extended into and retracted from the airstream, are provided to achieve directional control. Missile roll is utilized to achieve control in any direction with only one pair of aerodynamic surfaces, thereby enabling a light, simple, reliable control system.

A homing device, such as an infra-red seeker, provides electrical tracking rate information signals. The automatic pilot converts such tracking rate signals into electrical control signals, causing the control surfaces to extend or retract, properly phased in a manner suitable to maneuver the missile to intercept the target. The automatic pilot of the present invention causes the control surfaces to be extended for a period of time varying linearly with the magnitude of the seeker tracking rate signal. A lift force vector is produced during a portion of the roll cycle such that a force is applied to the missile to change course toward the target.

Heretofore known control systems for rolling missiles have been of the non-proportional on-off type. A combination of two control signals, one a signal wave and the other a reference wave, is employed to actuate a trigger circuit. The combination signal is compared with a fixed bias voltage in the trigger circuit, which changes condition when the applied signal becomes greater or less than the fixed bias voltage. A square pulse train output signal is produced by the trigger circuit, the width of the pulses varying in an inverse exponential manner with the amplitude of the applied combined signal.

As a result of the non-linear relationship, a large "dead space" exists about the zero error point, thereby increasing miss distance due to inability to correct for small errors. Further, missile dynamic stability is decreased, since large control signals are applied suddenly for comparatively small errors.

In contrast, the present invention provides a linear relationship between the period of control surface actuation and the magnitude of the seeker tracking rate signal. As a result, accuracy is improved by reducing miss distance, stresses on the missile are reduced, and effectiveness of the missile is increased.

It is, therefore, an object of this invention to provide a proportional rolling missile control system.

Another object of this invention is to provide a proportional sector autopilot for a rolling type of homing missile.

Another object of this invention is to increase the accuracy of a rolling type of homing missile.

Another object of this invention is to provide an automatic pilot for a rolling type of homing missile.

Another object of this invention is to provide an automatic pilot suitable for a rolling missile, which is simple, reliable, compact, and light in weight.

Other objects and features of the present invention will be readily apparent to those skilled in the art from

the following specification and appended drawings, wherein:

FIGURE 11 is a schematic view of a control surface actuating mechanism.

25 Referring now to FIGURE 1, a rolling missile incorporating the proportional automatic pilot of the present invention includes a seeker 11, an electronics section 12, a control section 13, a warhead 14, and a rocket motor 15. A presently preferred seeker 11, illustrated in FIGURE 2, is a free gyro stabilized, infra-red sensing mechanism. Seeker 11 provides an output signal representing the angular rate of rotation of the line of sight in space. The entire optical unit 16 rotates, forming a gyroscopic rotor mass. Spherical primary mirror 17 and secondary

30 mirror 18, forming a Cassegrainian type of reflecting telescope, reflect incident infra-red energy from a target such as a jet aircraft engine through a spinning reticle or chopper 21, illustrated by FIGURE 3, a filter 22, onto stationary infra-red responsive cell 23. Protective dome 24 and filter 22 are transparent to the desired region in the infra-red spectrum, filter 22 being opaque to other regions and serving as an optical band-pass filter.

35 Reticle 21, functioning in a manner well known to those skilled in the art, enables discrimination against such false targets as cloud edges, and permits sensing of tracking error by chopping the radiation passing to infrared responsive cell 23.

40 Referring now to FIGURES 4, 5 and 6, illustrated therein are motor coils 26a and 26b, employed to spin the optical head for gyroscopic effect, precession coils 27, and position sensing reference coils 28. A magnetic field actuated switch 31 is provided to alternately energize diametrically opposed motor field coils 26a and 26b. A permanent magnet 25, polarized in the plane of rotation, is mounted on parabolic mirror 17 for rotation with the optical system. A ring 32, made of a high permeability material such as the alloy commonly known as mu-metal, picks up flux from the magnet and carries it to magnetic switch 31. Operation of magnetic switch 31 is illustrated

45 in FIGURES 7 and 8. In FIGURE 7, flux collected by ring 32 flows through armature 33 in a direction aiding the normal armature-to-pole gap flux at the right hand side of the armature, and opposing the normal armature-to-pole gap flux at the left side, resulting in an unbalance of gap forces and closing the right hand gap. This closes the left hand contact, enabling current to flow in coil

50 26a, repelling the south pole of the rotor and attracting the north pole, resulting in clockwise rotation of the rotor. As the rotor rotates, the position of the poles changes, as illustrated in FIGURE 8, causing the flux in the armature

55 to reverse, enabling current to flow in coil 26b, resulting in an unbalance of gap forces and closing the left hand gap. This closes the right hand contact, enabling current to flow in coil

60 26b, repelling the north pole of the rotor and attracting the south pole, resulting in counter-clockwise rotation of the rotor. As the rotor rotates, the position of the poles changes, as illustrated in FIGURE 7, causing the flux in the armature

65 to reverse, enabling current to flow in coil 26a, repelling the south pole of the rotor and attracting the north pole, resulting in clockwise rotation of the rotor. As the rotor rotates, the position of the poles changes, as illustrated in FIGURE 8, causing the flux in the armature

70 to reverse, enabling current to flow in coil 26b, resulting in an unbalance of gap forces and closing the right hand gap. This closes the left hand contact, enabling current to flow in coil

in continuing clockwise rotation of the rotor. Switch 31 is positioned a few degrees in advance of the motor coil center line thus compensating for the inertia time constant of the switch armature. The rotor magnet is also phased approximately 30 degrees behind the reference radial on the rotating reticle. One-half of the reticle is 50% transparent, and the other half is furnished with transparent and opaque areas, as illustrated in FIGURE 3. Since the reticle revolves clockwise with the rotor, the reference radial referred to hereinabove is the radius at the right side of FIGURE 3 separating the semi-transparent area from the opaque-patterned area.

Directional control of a rolling missile is accomplished by extending a pair of fixed incidence wings, housed in section 13, during the period of the roll wherein a lift force is furnished to direct the missile to the target. The continuous roll required may be imparted to the missile by means of canted nozzles on the rocket motor, or by canted aerodynamic surfaces such as tail fins.

In the embodiment disclosed herein, the optical system, including reticle 21, is spun at a frequency f_0 with respect to the target. The missile itself is simultaneously rolling at a rate ϕ revolutions per second to enable production of a lifting force in any direction. Referring to FIGURE 9, the homing head senses the direction of flight path error in polar coordinates referenced to the roll axis of the missile, and extends the control surfaces during the proper portion of each revolution of the missile. A sinusoidal error signal of frequency f_0 , proportional in amplitude to the magnitude of the off-axis tracking error, and whose phase indicates the direction of the error, is supplied by the homing head. Reference coils 28, fixed to the rolling airframe and sensing the magnetic field of the seeker rotor generates a reference signal f_r having frequency $f_0 - \phi$, equal to the spin rate of the seeker head with respect to the missile airframe. The seeker and reference signals are applied to the automatic pilot circuit illustrated in FIGURE 10, which produces a wing-actuating signal having a frequency ϕ and a phase ϕ , as illustrated in FIGURE 9.

Amplifier 34 amplifies the signal generated by sensitive cell 23. Demodulator 35 serves to separate the modulating signal components from the chopper high frequency components of the amplified sinusoidal error signal f_0 from the infra-red sensitive cell 23. The error signal is applied to precession coils 27 through phase inverter 36 and push-pull power output amplifier 37. Precession coils 27, cooperating with magnet 25, serve to apply a force to the seeker head when energized by amplified signal f_0 to rotate the seeker head toward the target.

Signal f_0 from the demodulator 35 is also applied to signal squaring circuit 41 and to peak detector 42. Squaring circuit 41 serves to convert the sinusoidal signal f_0 into a square wave having the same frequency and phase relationship. Conveniently, such a squaring circuit may comprise an amplifier and limiter, or an overdriven amplifier, as is well known to those skilled in the art. Simultaneously, reference signal f_r , having a frequency $f_0 - \phi$, is supplied by reference coils 28 to squaring circuit 44, which may be similar to squaring circuit 41. The square wave from squaring circuit 44 is also applied to phase demodulator 43. Phase demodulator 43 provides a constant amplitude waveform output signal having the frequency components of a triangular waveform of a frequency ϕ and phase ϕ , as illustrated in FIGURE 9. High frequency components are removed by low pass filter 45, leaving the triangular wave signal. The triangular waveform is then applied to a summing circuit 46. Phase demodulator 43 produces a triangular output waveform as long as one of the two input signals is a square wave. The other input signal may be a sine wave. Phase demodulator 43 may be designed to be switched directly by a sine wave reference signal. Thus, squaring circuit 44 may be omitted.

The triangular variable phase signal has a constant amplitude. To provide proportional control, a D.C. bias signal varying proportionally with the seeker tracking rate is required. Peak detector 42, responsive to f_0 from demodulator 35, provides a direct voltage proportional to the amplitude of f_0 . High frequency components such as detector ripple, seeker noise, and transients are removed from the direct voltage signal by low pass filter 47.

The amplitude-proportional direct voltage and phase proportional triangular voltage are combined in summing circuit 46 and applied to electronic switch 51. The signal applied to switch 51 is a sawtooth; that is, the triangular phasing signal waveform is elevated by the direct voltage bias proportional to amplitude. Switch 51 may conveniently be a Schmitt trigger circuit, of a form well known to the art. Such circuits assume one condition when the applied voltage exceeds a predetermined value, and revert to their quiescent condition when the signal falls below the predetermined value. Conveniently, switch 51 conducts when the instantaneous sawtooth voltage exceeds a predetermined value set by a bias voltage, and cuts off when the instantaneous sawtooth voltage falls below the predetermined value. When switch 51 conducts, wing actuator 52 is energized, and the wings, or control surfaces, are extended.

It will be apparent, therefore, that the control surfaces are extended for a period during each revolution of the missile for the time that the sawtooth error signal is greater than the combined bias voltages. The center of 30 the portion of the roll cycle that the control surfaces are actuated coincides with the desired direction of lift. Similarly, the length of time the control surfaces are extended, labeled "lift sector" in FIGURE 9, is proportional to the magnitude of the direct bias voltage from 35 peak detector 42. In addition to a lift force in the desired direction, quadrature lift vectors on either side are also produced. However, these forces are equal and opposite, and cancel out. A large portion of the actual lift force is produced by the missile body, the wings, or more properly, control surfaces, serving mainly to change the angle of incidence of the elongated missile body. The angle of incidence of the body axis with respect to the flight path results in lift, deflecting the flight path toward the desired path. The lead angle of the reference coil, disclosed hereinabove, is provided to compensate for the time lag required for the wing actuating mechanism to extend and retract the control surfaces and to compensate for the phase lag in the filter following the phase demodulator, thereby enabling the net lift force of the control surfaces plus the body to act in the direction of the target.

Wing actuator 52 may be any convenient type of on-off servo system. Hydraulic or pneumatic system may be employed, with an electrically operated control valve 55 actuated by switch circuit 51. Preferably, however, electrical actuating means are employed. A suitable electrical actuator is schematically disclosed by FIGURE 11. A coil 53, connected to, and energized by, switch 51, pulls solenoid core 54 downwardly against tension spring 55. A yoke 56, connected to core 54, engages pin 57 on sector gear 61, rotating sector gear 61 about pivot 62. Sector gear 61 meshes with gear 62, journaled about pivot 63 and fastened to wing 64. Rotation of gear 62 results in extension of wing 64. Wing 65 is similarly rotated into the extended position by gear 66 and sector gear 67. When switch 51 is in the off position, spring 55, extended by solenoid core 54, returns core 54 to its normal position, retracting wings 64 and 65.

While a presently preferred embodiment of this invention has been disclosed hereinabove, it is understood that the invention is not limited thereto since many variations will be readily apparent to those skilled in the art, and is to be limited only by the scope of the appended claims.

nected to said amplifier, wave squaring means connected to said first detector, a phase detector connected to said wave squaring means and responsive to said second signal to generate a triangular wave signal, a peak detector responsive to said first signal for providing a direct voltage having a magnitude proportional to the amplitude of said first signal, an electronic switch connected to said phase detector and to said peak detector for providing a control actuating signal at a time determined by the phase of said triangular wave and for a period determined by the magnitude of said direct voltage, and control surface actuating means connected to said electronic switch.

9. In a rolling missile having an independently movable target seeker adapted to track a target and having a target radiation sensitive cell to generate a first signal having a phase indicating the direction of tracking error and amplitude indicating the magnitude of tracking error, and a reference coil to generate a second signal having a reference phase, a precession coil to aim said target seeker at said target, the combination of an amplifier connected to said radiation sensitive cell, a first detector connected to said amplifier, wave squaring means including a limiter connected to said first detector, a phase detector connected to said wave squaring means and responsive to said second signal to generate a triangular wave signal, a peak detector connected to said first detector for providing a direct voltage having a magnitude proportional to the amplitude of said first signal, an electronic switch connected to said phase detector and to said peak detector for providing a control actuating signal at a time determined by the phase of said triangular wave and for a period determined by the magnitude of said direct voltage, and electromagnetic control surface actuating means having a coil connected to said electronic switch.

10. In a rolling missile having an independently movable target seeker adapted to track a target and having a target radiation sensitive cell to generate a first signal having a phase indicating the direction of tracking error and amplitude indicating the magnitude of tracking error and a reference coil to generate a second signal having a reference phase, a precession coil to aim said target seeker at said target, the combination of an amplifier connected to said radiation sensitive cell, a first detector connected to said amplifier, wave squaring means including an amplifier and limiter connected to said first detector, a phase detector connected to said wave squaring means and responsive to said second signal to generate a triangular wave signal, a peak detector connected to said first detector for providing a direct voltage having a magnitude proportional to the amplitude of said first signal, an electronic switch connected to said phase detector and to said peak detector for providing a control actuating signal at a time determined by the phase of said triangular wave and for a period determined by the magnitude of said direct voltage, and electromagnetic control surface actuating means having a coil connected to said electronic switch.
